ADJUSTABLE ROLLING MILL GUIDE

Umbert F. Corsini, Worcester, Mass., assignor to
The American Steel and Wire Company of New
Jersey, a corporation of New Jersey

Application October 24, 1941, Serial No. 416,425

3 Claims. (Cl. 80—51)

This invention relates to improvements in adjustable guides for rolling mills, and more particularly to adjustable guide boxes for a rod mill or the like.

In rod mills and the like, multiple pass rolls are used, the work being guided to a selected pass or passes and then to other passes when those first selected become worn. Thus, it is desirable to have the guide box or boxes adjustable along the rolls in such a manner as to expedite such 10 pass changes with the requisite accuracy of alignment of the guides and passes.

It is a prime object of my invention to provide an improved guide of the character stated capable of ready and accurate adjustment in relation to the roll passes or grooves, thereby saving time and effort in the recurring operation of pass changing.

Further objects are to provide a device of the character stated which possesses both simplicity 20 and durability; to provide a device which may be readily applied to existing rolling mills; and to provide for the adjustment of the guides in direct relation to the pass spacing on the rolls.

Additional objects and advantages will become 25 apparent from the following description taken in connection with the accompanying drawings, wherein:

Fig. 1 is a front elevation of the receiving side of a rod mill stand, showing the application of 30 my invention thereto;

Fig. 2 is a cross section taken on the line II—II of Fig. 1.

Referring to the drawings, 2 designates the roll housings of a rod mill or the like, rotatably mounting a pair of rolls 3 and 4 in the usual manner. As illustrated, the said rolls are formed with a plurality of passes or grooves 5 having the desired configuration in accordance with the rod to be rolled thereby, said grooves being spaced equally along the length of the rolls.

My invention provides for the mounting and adjustment of one or more guide boxes transversely of the pass line of the mill, and to this end, includes horizontal guide frames 6 extending between and secured by their ends to the roll housings 2, as by means of screws 7, one of said frames being mounted on each of the receiving and delivery sides of the rolls. The frame on the receiving side is horizontally apertured at 8 and includes an upper rail 9 and a lower guide rail 10 defining said aperture. The guide or frame on the delivery side omits the said upper rail to permit free passage of the rod in case of a cobble or the like.

Guide boxes 11 are slidably mounted in said recesses 8 between the rails 9 and 10 of the receiving side frame, bearing on the rail 10 for non-rotating support. As illustrated in Fig. 1, two 5 of said boxes may be employed, and as preferred may be connected together as at 12 in the proper spacing according to the number of grooves or passes 5 in the rolls. Obviously, single guide boxes 11 may also be employed when desired. Guide boxes 11 are also slidably mounted on the single guide rail 10 on the delivery side of the mill.

For the purpose of translating the guide boxes 11 on the frames 6, each of said frames mounts 15 a screw 13 journaled by its ends in bearings 14 on the frame 6 outwardly beyond the terminals of the guide members 10. Each guide box includes a forwardly extending foot 15 threaded at 16 to receive the screw 13. The axis of the screw 13 and its engagement with the boxes 11 is in advance of the face of the frame 6 so as to be readily mounted on said frame, and the said axis is disposed below the pass line of the mill so as not to interfere with the passage of the rod or work.

The pitch of the thread of said screw 13 is equal to the axial distance between the center lines of the grooves or passes 5 of the rolls. Hence, upon mounting the box or boxes 11 and the screw 13 initially for alignment of said box or boxes with the groove or grooves 5 of the rolls, upon rotating said screw through one revolution, the box or boxes may be accurately moved to alignment with the next adjacent groove or grooves 5.

Each screw 13 extends at one end thereof for engagement by a hand crank 17 for rotation of said screw. By indexing the initial position of the handle 17 or screw 13, the box or boxes 11 may be readily adjusted along the rolls 3 and 4 between grooves 5 by rotation of the crank or screw into register with the index mark.

In order to rigidly secure the box or boxes 11 in adjusted alignment with the roll passes on the receiving side of the mill, the upper rail 9 of the frame 6 is slotted at 18 for receiving locking screws 19 threaded into the upper ends of the boxes 11. When said screws 19 are tightened upon the rail 8, the boxes 11 may be securely held in their selected position. Due to the ample bearing surfaces between the boxes 11 and rails 8 and 9, and the locking means 19, the boxes will be securely positioned in proper relation to the pass line of the mill.

As shown in Fig. 2, 20 designates the conventional form of guide secured in the boxes on the

receiving side of the mill, and 21 indicates the form of guide secured in the boxes on the delivery side of the mill, all of said guides being secured in their respective boxes 11 in the conventional manner.

Thus it will be seen that I have provided an adjustable guide means for rod mills and the like which may be easily and accurately adjusted for relation thereof with the selected grooves or passes of the rolls. Actual practice has shown that my invention effects a material saving in time and cost of mill operation, and results in an appreciable increase in production.

The invention has the further advantage of permitting the operator to readily make slight corrections in guide alignment with the roll passes to correct undesirable conditions which occur in operation. Thus, when it is observed that the rod is being rolled with a full side, the condition may be quickly remedied by slight guide adjustment by means of the screws 13.

Various changes and modifications are contemplated within the scope of the following claims.

I claim:

1. An adjustable guide for rolling mills having multiple grooved rolls, including a horizontal guide frame having upper and lower rails disposed transversely of the pass line of the mill, said rails being respectively disposed above and below said pass line, a guide box slidably mounted on the frame and disposed between said rails in non-rotatable relation, and a rotatably mounted adjusting screw having threaded engagement with the box for translation of the latter on the frame, said screw being mounted on the frame beneath the pass line of the mill, the pitch of said screw being equal to the axial distance between the center lines of the roll grooves, whereby the guide box may be selectively aligned with a roll groove by complete rotations of said screw, the length of the frame and the screw permitting adjustment of the guide box substantially throughout the width of the rolls.

2. An adjustable guide for rolling mills having multiple grooved rolls, including a horizontal guide frame having a pair of spaced rails disposed transversely of the pass line of the mill, a guide box slidably mounted on the rails in non-rotatable relation, and a rotatably mounted adjusting screw having threaded engagement with the box for translation of the latter on the frame, said screw being mounted on the frame and spaced from the pass line of the mill, the pitch of the screw being equal to the axial distance between the center lines of the grooves on the rolls, whereby the guide box may be selectively aligned with a roll groove by complete rotations of said screw, the length of the frame and the screw permitting adjustment of the guide box substantially throughout the width of the rolls.

3. An adjustable guide for rolling mills having multiple grooved rolls, including a horizontal guide frame having upper and lower rails disposed transversely of the pass line of the mill, a pair of spaced guide boxes slidably mounted on the frame and disposed between said rails in non-rotatable relation, said guide boxes being spaced apart transversely of said pass line in alignment with a pair of spaced grooves in said rolls, a rotatably mounted adjusting screw having threaded engagement with the boxes for translation of the latter on the frame in said spaced relation, said screw being mounted on the frame beneath the pass line of the mill, the pitch of said screw being equal to the axial distance between the center lines of the roll grooves, whereby the guide boxes may be selectively aligned with pairs of roll grooves by complete rotations of said screw, the length of the frame and the screw permitting adjustment of the guide boxes substantially throughout the width of the rolls, and locking means on the boxes coacting with one of the said rails of the frame for securing the boxes in adjusted position.

UMBERT F. CORSINI.
